MEANS FOR DEFLATING PNEUMATIC TUBES

Walter V. Smith, South Hadley Falls, Mass., assignor to The Fisk Rubber Company, Chicopee Falls, Mass., a corporation of Massachusetts

Application March 7, 1930. Serial No. 434,093

1 Claim. (Cl. 152—12)

My invention relates to apparatus for deflating pneumatic tubes such, for example, as the inner tubes used in pneumatic tires which are provided with valves normally holding the air in the tubes. 5 At certain stages during the manufacture of such tubes as, for example, during inspection it is customary to inflate, or partially inflate, the tubes and it is then necessary to later deflate the tubes for the purpose of wrapping and packaging or for 10 other operations. Various devices are now in use for rapidly withdrawing the air from the tubes but such devices are relatively complicated. It is the object of my invention to provide apparatus by which the tubes may be deflated in an expeditious manner and at a saving in cost and to provide a device for carrying out the invention which shall be simple in construction and efficient in operation.

In the accompanying drawing which illustrates 20 one embodiment of my structure,

Fig. 1 is a plan view showing a tube in deflating position;

Fig. 2 is a side elevation taken substantially 25 along lines 2—2 of Fig. 1, being partly in section and on an enlarged scale, showing one of the deflating heads;

Fig. 3 is a section on line 3—3 of Fig. 2, showing the valve in deflating position;

Fig. 4 is a similar view showing the valve in 30 venting position;

Fig. 5 is a detail view, partly in section, showing a deflating cap in position on the end of the valve stem; and

Fig. 6 is a section on line 6—6 of Fig. 1.

According to my invention at the end of the 35 inspection or testing operation I apply to the end of the valve stem a deflating cap having resilient side walls such, for example, as the cap disclosed and claimed in Patent No. 1,876,715 issued September 13, 1932 on an application by Charles Edgar Maynard, which cap is shown in the accompanying drawing for purpose of illustration.

The deflating cap, generally indicated at 10, is held to the valve stem 11 of the tube 12 by 40 the resiliency of its walls and is provided with a pin 13 which holds the valve of the stem open permitting escape of the air in the tube through passages 14 in the cap. During the transfer of the tube from the inspecting or testing station 45 to the deflating means a substantial amount of the enclosed air is expelled. The pressure, however, is not sufficient to completely expel the air from the tube and this is accomplished by the application of a vacuum. My improved mechanism 50 for this latter step comprises a deflating

head 15, a number of which may be connected as by T's 16 to a vacuum line 17. The head 15 is provided with a valve 19 which, when the valve parts are shown in the position of Fig. 3, open the vacuum to nozzle 20 projecting from 60 the head 15. The free end of nozzle 20 is of a diameter substantially the same, or slightly smaller, than the normal diameter of the inflating cap 10 carried by the valve stem 11 so that when the end of the valve stem is forced 65 into nozzle 20 the resilient walls of the cap, particularly the shoulder 18, formed by straining the cap over the end of the stem, forms a seal between the valve stem and the nozzle. The lower wall of the nozzle is extended as at 21 to 70 form a support which engages the valve stem to support the tube in deflating position. The extension 21 is preferably bent slightly upward as indicated at 22 to hold the valve stem in line with the axis of the nozzle 20 and the outer end 75 of the extension is also preferably curved downward as at 23 to accommodate angle or bent types of valve stems. It will be apparent that the downwardly bent portion 23 does not interfere with the use of the device for straight valves. 80 With the valve stem of the tube to be deflated positioned as above described and as shown in dotted lines in Fig. 2, valve 19 is opened as shown in Fig. 3 and the air completely removed from the tube by the vacuum. In normal operation 85 one operator handles a plurality of deflating heads and it may happen that when he comes to remove the tube from a head the application of the vacuum has been sufficient to not only withdraw the air from the tube but to wrinkle or 90 otherwise deform it due to the creation of a partial vacuum in the tube itself. To correct this condition, and to break the vacuum so that valve stem and cap may be easily removed, the valve 19 is turned to the position shown in Fig. 4 95 to cut off the vacuum and vent the nozzle and tube to the atmosphere through a small aperture 25 in the head 15, permitting sufficient air to enter the tube to allow the tube to return to normal deflated condition.

Where high vacuum is used or the deflating cap does not make a sufficiently tight fit in the end of nozzle 20 the cap 10 may be drawn from the end of the stem 11 into the nozzle 20 and to prevent this I provide a transverse pin 26 adja- 100 cent the end of the nozzle which prevents passage of the deflating cap too far into the nozzle.

Having thus described my invention, I claim:

In a vacuum device for deflating pneumatic tubes having valved stems, wherein the stem of 110

2

each tube is provided with a rubber valve opening cap, a head connected to a vacuum line, a nozzle projecting from the head, said nozzle having an interior diameter such as to receive and make a sealing engagement with the rubber cap on the valve stem of the tube to be deflated when the capped end of the stem is forcibly telescoped

into the nozzle, and valve mechanism in the head operable in one position to supply vacuum to the nozzle to evacuate the tube and in a second position to permit atmospheric pressure to enter the tube.
